UNITED STATES PATENT OFFICE.

EMIL FOX, OF NEW YORK, N. Y., ASSIGNOR TO WM. MANNHEIM & CO., OF SAME PLACE.

DESIGN FOR A BOX-LOOP FOR HARNESS.

SPECIFICATION forming part of Design No 20,719, dated May 12, 1891.

Application filed March 20, 1891. Serial No. 385,824. Term of patent: 14 years.

To all whom it may concern:

Be it known that I, EMIL FOX, of the city, county, and State of New York, a citizen of the United States, have invented and produced a new and original Design for Box-Loops for Harness, of which the following is a specification.

This invention relates to a design for the box-loops of harness; and it consists of a central embossed square and angular embossed ribs from the central square to the ends of the box-loop and a plain frame of raised lines surrounding said angular ribs.

The nature of my design is shown in the accompanying drawing, in which a top view of the box-loop is shown and to which reference is made.

A in the drawing represents a box-loop for harness, the face of which is ornamented by a raised diamond or square *a* in the center and by a series of angular ribs *b*, arranged

symmetrically at both sides of the center diamond or square *a* to the ends of the box-loop. The ribs are surrounded by an oblong frame *d* of raised lines.

25

Having thus described my invention, I claim as new and desire to secure by Letters Patent—

A design for the face of a box-loop for a harness, composed of a central diamond or square 30 and a series of angular ribs arranged immediately between the diamond or square and the ends of the box-loop, said ribs being surrounded by an oblong raised frame, substantially as set forth.

35

In testimony that I claim the foregoing as my invention I have signed my name in presence of two subscribing witnesses.

EMIL FOX.
